CLAIM

The ornamental design for a container body panel, as shown and described.

DESCRIPTION

FIG. 1 is a front elevational view of a container body panel showing our new design, the container shown in broken lines for illustrative purposes only;

FIG. 2 is an enlarged rear elevational view thereof;

FIG. 3 is a left front perspective view of FIG. 2; and, FIG. 4 is a top plan view of FIG. 2, the bottom being a mirror image.
